UNITED STATES PATENT OFFICE.

WILLIAM L. WHITE, OF OLD ORCHARD, MAINE.

DESIGN FOR A CASTER FOR CRUETS.

55,496.

Specification for Design. Patented June 15, 1920.

Application filed July 5, 1919. Serial No. 308,907. Term of patent 7 years.

To all whom it may concern:

Be it known that I, WILLIAM L. WHITE, a citizen of the United States, residing at Old Orchard, in the county of York and State of Maine, have invented a new, original, and ornamental Design for a Caster for Cruets, of which the following is a specification, reference being had to the accompanying drawing, forming part thereof.

The figure of the drawing is a perspective view of a caster for cruets showing my new design.

I claim:

The ornamental design for a caster for cruets, as shown.

In testimony whereof I have hereunto set my hand in presence of two subscribing witnesses.

WILLIAM L. WHITE.
